UNITED STATES PATENT OFFICE

WILLIAM EBKE, OF HELVEY, NEBRASKA

OIL BURNER

Application filed August 24, 1929. Serial No. 388,100.

My invention relates to oil burners, its primary object being the provision of an oil burner construction which is so designed that the flame cannot be extinguished under violent fluctuations of wind pressures.

Another of my objects is the provision of structures which make it easy to assemble and disassemble the parts of the oil burner so that easy access may be obtained to the working parts and so that the oil burner will be "fool proof" in the hands of inexperienced operators.

My oil burner is designed specifically for use in connection with heaters for brooders, incubators, farrowing houses and the like where the draft within the burner is subjected to all of the fluctuations of wind pressures.

Having in view these objects and others which will be pointed out in the following description, I will now refer to the drawings, in which

Figure 1 is a plan view of my oil burner.

Figure 2 is a median vertical sectional view of the assembled oil burner.

Figure 3 is a view in perspective of the base of my oil burner.

Figure 4 is a perspective view of the tuyère cover.

Figure 5 is a view in perspective of the flame spreader.

My oil burner includes a base 10, a tuyère cover 11 and a flame spreader 12. The base is provided with a plurality of bolt holes 13 for securing the entire burner in place. A peripheral wall 14 rises from the base, this wall being designed for the purpose of supporting a heating drum which surrounds the burner, the heating drum being not shown since it forms no part of my present invention and since its construction and function are well understood by all those skilled in the art. The oil is fed through an aperture 15 into a central cup 16 on the base. The walls of this cup rise to a level which is intermediate the top and bottom surfaces of the tuyère cover as shown in Figure 2. The tuyère cover is provided with a central aperture 17 and above this is the flame spreader 12. As is common to all burners of this type, the flame

strikes the flame spreader and is thus directed outwardly toward the drum of the heater. The cup 16 is surrounded by an annular channel 18 for receiving the overflow from the cup 16. The base is also provided with a drain 19 for the overflow, the oil being conducted from a drain to a suitable container at some distance from the burner. Thus far the construction is more or less common to all burners of this type.

The base 10 is provided with two openings 20 for the admission of air to the burner, the openings being diametrically opposite each other. Two walls 21 rise from the base 10, the walls being parallel except at the middle where they are bowed out in the form of circular arcs. The openings 20 lie entirely between the two walls 21. The two walls 21 are connected by means of a pair of transverse walls 22 which are somewhat lower in height than the walls 21. The air entering the openings 20 must thus pass over the top edges of the walls 22 before it can reach the flame. The walls 22 have also another function in that they with the walls 21 enclose the space surrounding the burner so that the accidental overflow of oil cannot reach the openings 20. The peripheral wall 14 is slightly raised between the walls 21 as shown in Figure 3.

The tuyère cover 11 has edge walls 23 so dimensioned that they will lie outside and in close contact with the walls 21. The walls 23 are also bowed in their middle portion to conform to the shape of the walls 21. The walls 23 are notched at their ends so that the tuyère cover readily seats over the walls 21 and over the raised portions of the wall 14. In order to still further facilitate this seating I provide an annular rib 24 which is so dimensioned that it seats within the bowed portion of the walls 21. Since both the base 10 and the tuyère cover 11 are symmetrical throughout, it is evident that the tuyère cover may be placed on the base in either of two positions and that it will readily seat on the base without any effort. When thus seated the cover makes reasonably tight joints with the walls 21 and with the raised portions of the peripheral wall 14.

The current of air entering through the openings 20 varies in intensity between rather wide limits. Burners of this type are usually provided with thermostats which automatically control the feed of oil to the burner. The thermostat arrangement is very effective for this purpose but an additional difficulty is encountered in climates where the force of the wind varies in intensity between 10 wide limits. In all other burners, so far as I am aware, a strong wind entering through the openings 20 will extinguish the flame at the mouth of the cup 16 and this is often followed by disastrous results unless it is discovered in time. In order to prevent this I provide a series of baffles so designed and arranged as to effectively break the force of a strong wind without materially affecting the movement of a gentle current of air through 20 the burner. As shown in Figure 4, the tuyère cover has four legs or baffles 25 which are wedge shaped or tapered in length and oval in cross-section. The wider portions of the oval of the baffles 25 are placed facing 25 the openings 20 whereby a relatively large area of the baffles is presented to the incoming air so that the force of a strong wind will be effectively broken up. The bottoms of these legs rest on the base 10, as shown 30 in Figure 2, and thus assist in supporting the tuyère cover. Their primary function, however, is to deflect the air currents passing over the walls or baffles 22 before the air currents reach the flame. The legs or baffles 35 25 are spaced from each other and from the walls 23. The current of air striking these baffles 25 will be deflected laterally and their force will be broken so that the flame cannot be extinguished. The shape of these baffles, however, is such as to reduce to a 40 minimum the friction encountered by a gentle current of air which moves freely toward the flame without appreciable obstruction from the baffles.

45 The base 10, the tuyère cover 11 and the flame spreader 12 are each of integral construction, being preferably formed from cast iron. The base is further provided with a pair of spaced apart ribs 26 which assist 50 in directing the overflow of fuel toward the drain 19. The flame spreader 12 is pivotally secured at 27 to the tuyère cover 11 so that it is movable in order to give access to the flame opening 17 as when lighting the burner. It is provided also with a stop 28 which permits swinging movement in one direction only and which limits the movement toward 55 operative position so that the flame spreader is in its most effective position.

Having thus described my invention in such full, clear, and exact terms that its construction and operation will be readily understood by others skilled in the art to 60 which it pertains, what I claim as new and

desire to secure by Letters Patent of the United States is:

1. An oil burner including a circular base having a fuel cup and a central conduit for conducting liquid fuel to said cup, said base being provided with a pair of diametrically opposed openings for admitting air therethrough, upstanding walls on said base forming a pair of aligned tuyères for conducting the air from the openings to the cup, a cover for said tuyères, said cover being provided with an opening, and baffles depending from said cover, said baffles being positioned obliquely in pairs in said tuyères and with the baffles of each pair converging toward the cup for breaking the force of the air currents. 70
2. An oil burner including a circular base having a fuel cup and a central conduit for conducting liquid fuel to said cup, said base being provided with a pair of diametrically opposed openings for admitting air therethrough, upstanding walls on said base forming tuyères for conducting the air from the openings to the cup, an upwardly projecting baffle in each of said tuyères adjacent the inlet opening thereof, a cover for said tuyères, said cover being provided with an opening, and baffles depending from said cover, said baffles being positioned obliquely in pairs in said tuyères and with the baffles of each pair converging toward the cup for breaking the force of the air currents. 75 80
3. An oil burner including a circular base having a fuel cup and a central conduit for conducting liquid fuel to said cup, said base being provided with a pair of diametrically opposed openings for admitting air therethrough, upstanding walls on said base forming a pair of aligned tuyères for conducting the air from the openings to the cup, a cover for said tuyères, said cover being provided with an opening, and baffles depending from said cover, said baffles being positioned obliquely in said tuyères for breaking the force of the air currents, said baffles being tapered and being oval in horizontal section and positioned with the wider portion of the oval receiving the force of the air current. 95 100 105

In testimony whereof I affix my signature. 110
